(57) **CLAIM**

The ornamental design for a monitor outlet, as shown and described.

DESCRIPTION

FIG. 1 is a front view of a monitor outlet, showing our new design;

FIG. 2 is a front perspective view thereof; and,
FIG. 3 is an enlarged view of the indicated portion of FIG. 2.

Broken lines in the drawings denote features of the article that are included for the purpose of illustrating context, but form no part of the claimed design. Similarly, square boundary lines illustrated in dash-dot-dash form no part of the claimed design.
